UNITED STATES PATENT OFFICE.

HENRY M. WATCHORN, OF SAPULPA, OKLAHOMA.

TUNNELING DEVICE.

Application filed October 28, 1927. Serial No. 229,432.

My invention relates to improvements in tunneling devices, and it consists in the combinations, constructions, and arrangements herein described and claimed.

5 An object of my invention is to provide a tunneling device which is adapted to bore holes in the ground beneath streets, alleys, houses, or the like for the laying of pipe without injuring in any way the structure beneath which it is boring.

10 A further object of my invention is to provide a device of the type described which employs the pipe to be laid as a means through which the loosened substance of the ground is removed.

15 A further object of my invention is to provide a device of the type described by means of which the pipe which is to be placed in the drilled tunnel is gradually moved into place as the tunnel is being formed.

20 A further object of my invention is to provide a device of the type described which has novel means for adjusting the position or the slant of the ground-engaging portions with respect to the supporting frame.

25 A further object of my invention is to provide a device of the type described to which detachable power means may be applied.

30 A further object of my invention is to provide a device of the type described which has novel means for moving the tunneling means forwardly or rearwardly.

35 Other objects and advantages will appear in the following specification, and the novel features of the invention will be particularly pointed out in the appended claims.

My invention is illustrated in the accompanying drawings, forming part of this application, in which

40 Figure 1 is a side elevation of my device, Figure 2 is a plan view of my device, Figure 3 is a section substantially along the line 3—3 of Figure 1, and

45 Figure 4 is an end elevation of my device, a portion thereof being broken away.

In carrying out my invention, I provide a stationary outer frame 1 having guides 2 formed of channel iron. The frame 1 is mounted upon runners 3 which have eyelets 4 and 5 secured to the front and rear ends respectively thereof.

50 A movable frame 6 is disposed in the stationary frame 1 and is provided with four guide rollers 7 which are rotatably mounted upon each end thereof. The guide rollers 7 are receivable in the guides 2 which serve as

tracks for the rollers. Adjusting screws 8 are carried by each end of the stationary frame 1 and are receivable in an internally threaded lug 9 upon each end of the movable frame 6. The upper ends of the adjusting screws are arranged to receive any ordinary rotating means, such as a crank or wrench, not shown.

55 A power shaft 10, to which any suitable power, not shown, may be attached, such as an electric motor or a gasoline engine, is mounted upon the frame 1 in a bearing 11. A drive shaft 12 is disposed at right angles with respect to the power shaft 10 and longitudinally with respect to the frame 6. The

drive shaft 12 is rotatably supported by bearings 13 upon each end of the frame 6, and a relatively large bearing 14 is positioned in close proximity to the power shaft 10. The

70 power shaft is operatively connected to the drive shaft by means of a beveled gear 15 which is mounted upon the power shaft and a beveled gear 16 which is mounted upon the drive shaft, these gears being in mesh. A

75 relatively small driven shaft 17 is positioned beneath and in parallel relation with the drive shaft 12. The driven shaft 17 is operatively connected to the drive shaft 12 by a gear 18 which is mounted upon the driven shaft and a gear 19 which is mounted upon the drive shaft, these gears being in mesh.

80 An auger 20 is rotatably disposed in a tube 21 which is rotatably mounted in bearings 22. The bearings 22 are rigidly mounted in the 90 frame 6. The rear end of the auger 20 is rigidly mounted in a bearing 23 which is rigidly mounted in the frame 6. The auger 20 is operatively connected to the driven shaft 17 by means of a chain 24 which passes over a sprocket wheel 25 mounted upon the driven shaft 17 and a sprocket wheel 26 mounted upon the auger 20.

85 The tube 21 is operatively connected to the drive shaft 12 by means of a chain 27 which 100 extends over a relatively small sprocket wheel 28 which is rigidly mounted upon the drive shaft 12, and a relatively large sprocket wheel 29 which is rigidly mounted upon the tube 21. Elongated openings 30 are provided in the tube 21 for a purpose hereinafter described.

90 A flange union 31 is rigidly mounted upon the tube 21 and is arranged to receive a pipe 32. The pipe 32 may be formed of sections 110 of standard lengths. The auger 20 may also be formed by a certain number of standard

lengths equal in number to the number of lengths of pipe 32 used. A boring bit 33 having cutters 34 extending transversely with respect to each other is rigidly secured 5 to the end of the pipe 32 by means of a coupling 35. The bit 33 is provided with cut-away portions 36 for a purpose hereinafter described.

A winch 37 having a central partition 38 10 is rigidly mounted upon a shaft 39 which is rotatably mounted in bearings 40. A relatively large sprocket wheel 41 is rigidly mounted upon the shaft 39 and is operatively connected to a relatively small sprocket wheel 15 42 by means of a chain 43. The sprocket wheel 42 is rigidly mounted upon one end of a relatively small shaft 44. A beveled gear 45 is rigidly mounted upon the other end of the shaft 44. Beveled gears 46 and 47 are 20 movably disposed upon the drive shaft 12 but are made to rotate with the shaft 12 by means of keys 48 and 49. A U-shaped gear-moving member 50 is movably disposed in bearings 51 upon the frame 6 and is operatively connected to the beveled gears 46 and 47. 25 The member 50 is arranged to be moved by means of a lever 52 which is pivotally mounted at 53 upon the frame 6.

A wire rope 54 is secured to the eyelets 4 30 and passes through a pulley 55. The pulley 55 is mounted upon a support 56. The wire rope 54 passes over a pulley 57 which is rotatably carried by the frame 6, and then is wound around the winch 37 upon one side 35 of the partition 38. Another wire rope 58 which is wound around the winch upon the other side of the partition 38 passes over a pulley 59 and may pass through another pulley similar to that shown at 55. The free end 40 of the wire rope 58 is then secured to the eyelets 5.

From the foregoing description of the various parts of the device, the operation thereof may be readily understood. Let us 45 assume that the operator wishes to tunnel beneath a street, indicated at 60. A ditch 61 is first dug at the side of the street and at right angles with respect thereto. The ditch 61 is sufficiently large to receive the device and 50 long enough to allow longitudinal movement of the device therein. The first length of pipe 32 and the first length of auger 20 are secured in place. The position of the pipe and auger may be adjusted with respect to the street by 55 actuating the adjusting screws 8 to raise or lower the tube and auger. It is obvious that the tube and auger may be tilted to a desired angle by actuating only one of the adjusting screws 8. When the movable frame 6, together with its cooperating parts, mainly the pipe 32 and the auger, have been adjusted to the desired position with respect to the level 60 of the street, the support 56 may be rigidly secured in place by any suitable means.

65 As stated heretofore, any suitable power

means may be operatively connected to the power shaft 10 for rotating the power shaft in a clockwise direction. The rotation of the power shaft 10 in a clockwise direction will rotate the drive shaft 12 in a clockwise direction, looking at the rear of the frame 6. The driven shaft 17 will therefore be rotated in a counter-clockwise direction, and as the auger 20 is operatively connected to the driven shaft 17, the auger will be rotated in a counter-clockwise direction. The tube 21 which is operatively connected to the drive shaft 12 will be rotated in a clockwise direction. Therefore, the auger will be rotated at approximately the speed of the shaft 17 in a counter-clockwise direction while the tube 21 will be rotated at a much slower speed, due to the reduction of the sprockets 29 and 28, in a clockwise direction.

As shown in Figure 2, the beveled gear 47 85 is moved into mesh with the beveled gear 45. Therefore, the winch 37 will be rotated in a clockwise direction, causing the wire rope 54 to wind upon the winch. In this manner, the entire device will be moved forwardly within the ditch 61, the runners 3 sliding upon the bottom of the ditch.

This forward movement causes the rotating pipe and drill bit to be forced into the ground beneath the street. It is obvious that the only outlet for the matter made loose by the drill bit is through the pipe 32. The cutaway portions 36 allow the loosened matter to readily be forced into the pipe where it is received by the auger and moved rearwardly within the pipe, due to the fact that the auger is being rotated in the opposite direction to that of the pipe. As the auger is rotated at a faster speed than the rotation of the pipe, the loosened dirt may be readily removed from the drill bit so as not to interfere with the operation thereof. As the loosened matter is drawn rearwardly, it is brought into registration with the elongated openings 30 and allowed to pass therethrough. When the device has almost reached the forward end of the ditch 61, the flange union 31 may be uncoupled and the device moved rearwardly a sufficient distance to allow another section of pipe and still another section of auger to be attached thereto and to the first section of pipe and auger.

To move the device rearwardly, the beveled gear 47 is moved out of mesh with the beveled gear 45, and the beveled gear 46 is moved in mesh with the beveled gear 45 by actuating the lever 52. When this is accomplished, the winch will be rotated in a counterclockwise direction, causing the wire rope 58 to wind upon the winch 37 and draw the device rearwardly within the ditch 61. The device may again be moved forwardly by actuating the lever 52 to bring the beveled gear 47 in mesh with the beveled gear 45. This operation may be continued, adding as many lengths of pipe 130

and auger as is needed to extend beneath the street 60. When this has been accomplished, the sections of pipe may be released from the flange union 31 and the sections of auger may be removed from the sections of pipe one at a time. The drill bit may be removed from the first section of pipe at the other side of the street. It is obvious therefore that a hole may be tunneled beneath a street, the pipe 10 which is to be used serving as a portion of the tunneling means and the pipe remaining in the tunneled opening ready for use. It is also obvious that the device may be used for tunneling beneath alleys, buildings, or the 15 like.

I claim :

1. A device of the type described comprising a stationary frame, runners for said stationary frame, a movable frame disposed in 20 said stationary frame, tunneling means carried by said movable frame, means for moving said movable frame with respect to said stationary frame for varying the position of said tunneling means with respect to said 25 stationary frame, means carried by said movable frame for moving said frames and said tunneling means in one direction, and means cooperating with said moving means for moving said frames and said tunneling means in 30 the opposite direction.

2. A device of the type described comprising runners, a stationary frame mounted upon said runners, a movable frame disposed in said stationary frame, means for moving 35 said movable frame with respect to said stationary frame, tunneling means carried by said movable frame, said tunneling means comprising a tube having elongated openings therein, a main auger rotatably disposed in 40 said tube, a pipe, means for securing one end of said pipe to said tube, an auxiliary auger disposed in said pipe and rigidly secured to said main auger, a drill bit secured to the other end of said pipe, means for rotating 45 said tube, said pipe and said drill bit in one direction, means for rotating said augers in the opposite direction, and means carried by said movable frame and operatively connected to said runners for moving said frames

and said tunneling means in one direction for 50 moving the drill bit and the pipe into the ground, the rotation of said drill bit during the movement into the ground forms an opening therein, said drill bit being arranged to allow the loosened matter to pass into said pipe, the rotation of said augers being adapted 55 to move the loosened matter through said pipe, said tube and said openings.

3. A device of the type described comprising runners, a stationary frame mounted upon said runners, a movable frame disposed in said stationary frame, means for moving 60 said movable frame with respect to said stationary frame, tunneling means carried by said movable frame, said tunneling means comprising a tube having elongated openings 65 therein, a main auger rotatably disposed in said tube, a pipe, means for securing one end of said pipe to said tube, an auxiliary auger disposed in said pipe and rigidly secured to said main auger, a drill bit secured to the other end of said pipe, means for rotating 70 said tube, said pipe and said drill bit in one direction, means for rotating said augers in the opposite direction, means carried by said 75 movable frame and operatively connected to said runners for moving said frames and said tunneling means in one direction for moving the drill bit and the pipe into the ground, the rotation of said drill bit during the movement 80 into the ground forms an opening therein, said drill bit being arranged to allow the loosened matter to pass into said pipe, the rotation of said augers being adapted to move the loosened matter through said pipe, said 85 tube and said openings, said pipe arranged to be removed from said tube, said auxiliary auger arranged to be removed from said main auger, means cooperating with said moving means for moving said frames, said tube and 90 said main auger in the opposite direction, a second pipe having one end secured to said tube and the other end secured to said first named pipe, and a second auxiliary auger having one end secured to said main auger 95 and the other end secured to said first named auxiliary auger.

HENRY M. WATCHORN.
